UNITED STATES PATENT OFFICE.

EDWARD F. SMITH, OF CINCINNATI, OHIO, ASSIGNOR TO THE LEKTRO MANUFACTURING COMPANY, OF CINCINNATI, OHIO, A FIRM.

DESIGN FOR A HOUSING FOR ELECTRIC DRILLS.

No. 38,945.

Specification for Design.

Patented Dec. 10, 1907.

Application filed November 2, 1906. Serial No. 341,803. Term of patent 7 years.

To all whom it may concern:

Be it known that I, EDWARD F. SMITH, a citizen of the United States, and residing at Cincinnati, Hamilton county, State of Ohio, have invented a certain new, original, and ornamental Design for a Housing for Electric Drills, reference being had to the accompanying drawing, which shows my design.

Figure 1, is a rear-elevation. Fig. 2, is a side-elevation and Fig. 3, is a front elevation,

showing the design of the electric drill housing.

I claim:

The ornamental design for a housing for electric drills as shown.

EDWARD F. SMITH.

Witnesses:

C. SPENGEL,
T. LE BEAU.
